CLAIM

The ornamental design for a transport robot, as shown and described.

DESCRIPTION

FIG. 1 is a front view of a transport robot according to the present application, showing our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof;

FIG. 8 is a second perspective view thereof;

FIG. 9 is an enlarged view taken along line 9 of FIG. 1; and,

FIG. 10 is an enlarged view taken along line 10 of FIG. 2. The broken lines in FIGS. 1, 2, 9 and 10 are to show enlarged portions of the transport robot and form no part of the claimed design.
